FRANK J. DELANY AND ARTHUR H. SMITH, OF CHICAGO, ILLINOIS.

DEVICE FOR IMPROVING COMBUSTION.

1,197,918

Specification of Letters Patent. Patented Sept. 12, 1916.

Application filed June 21, 1915. Serial No. 35,198.

To all whom it may concern:

Be it known that we, FRANK J. DELANY and ARTHUR H. SMITH, citizens of the United States, residing at Chicago, county 5 of Cook, State of Illinois, have invented a certain new and useful Improvement in Devices for Improving Combustion, and declare the following to be a full, clear, and exact description of the same, such as will 10 enable others skilled in the art to which it pertains to make and use the same, reference being had to the accompanying drawings, which form a part of this specification.

It is well known that the introduction of 15 oxygen into the combustion chambers of furnaces insures the combustion of combustible materials, both solid and gaseous, which would otherwise be wasted. There has, however, been no wide successful application of this principle to furnaces, beyond 20 the simple expedient of air inlets in furnace doors, because of the difficulty of securing a simple reliable device which would not be in the way during the firing 25 operation, or require a reorganization of the furnace; for its installation, or require careful attention, or introduce the oxygen in a cold state and cause the fire to burn less effectively than it would without the added 30 attachment.

The object of the present invention is to produce a simple and novel attachment which may be installed in furnaces without interfering in any way with the construction or operation of the furnaces and 35 will insure an adequate supply of heated oxygen in the combustion chamber and thus produce practically perfect combustion.

A further object of the present invention 40 is to produce a simple air-supplying attachment which is capable of being located and adjusted in a great variety of positions in a furnace so as to permit it to be placed in the most advantageous position with respect 45 to the fire in any particular furnace.

A further object of the present invention is to produce a simple air-supplying attachment adapted to be located in part in the door opening of a furnace and in part in the 50 combustion chamber and to coöperate with the usual air hole in the furnace door to receive outside air and deliver it into the combustion chamber in a heated state.

The various features of novelty whereby 55 our invention is characterized will herein-after be pointed out with particularity in

the claims; but, for a full understanding of our invention and of its objects and advantages, reference may be had to the following detailed description taken in connection with the accompanying drawings, wherein:

Figure 1 is a vertical section through a furnace containing our attachment, taken on a plane within the combustion chamber and looking toward the door; Fig. 2 is a 65 vertical longitudinal section taken through the door approximately on line 2—2 of Fig. 3; Fig. 3 is a horizontal section through the furnace on a plane passing through the door; Fig. 4 is a vertical section on an enlarged scale through one of the heat inter-changers; and Fig. 5 is an enlarged view, partly in section, of the universal joint between one of the heat inter-changers and the air-supplying conduit.

In the drawings we have illustrated only a single simple form of our invention and, for the sake of brevity, we shall confine the detailed description to this particular embodiment; but we desire that it be clearly understood that our invention is not limited to this one embodiment but may take various other structural forms.

Referring to the drawings, 1 represents a furnace having a door opening, 2, controlled by a door, 3, and leading to the combustion chamber, 4. All these parts may be of any usual or suitable form and construction. In accordance with our invention, we place a broad shallow conduit, 5, within and at any one of the several sides of the door opening; the inlet end of the conduit communicating with an air chamber, 6, between a plate, 7, and the door to which the plate is attached. The plate, 7, extends from the 95 side of the door corresponding to the side of the opening in which the conduit lies, at least past the usual air inlet, 8, in the door; so that air may enter the inlet, pass through the chamber, 6, and then into the conduit, 5. 100

The conduit, 5, being shallow, does not appreciably obstruct the door opening and, being supported independently of the door, is not limited in size or shape by the necessity of swinging in and out as the door is 105 closed and opened.

At the inner end of the conduit, and preferably at the corners thereof, are heat inter-changing devices adapted to lie within the combustion chamber of the furnace beside 110 and without obstructing the door opening. In the arrangement illustrated there are two

of these heat interchangers 9, 9, each in the form of a flat rectangular metal box containing a plurality of longitudinal partitions, 10, so disposed that air passing from 5 the air inlet, 11, at one side to the outlet, 12, at the other side follows a long zigzag path. Each heat interchanger is connected at its inlet, 11, to one inner corner of the conduit, 5, preferably by a universal joint, 14, which 10 permits the interchanger to be disposed at any desired angle to the supporting conduit. The outlets, 12, are preferably in the form of long narrow slots which permit the air to 15 pass out into the combustion chamber in wide thin sheets.

Assuming the parts to be adjusted as illustrated in the drawings, with a fire burning in the furnace: it will be seen that the heat interchangers will become very hot so that 20 air flowing into and through the same, and which is partially heated in the chamber 6 and conduit 5, will become highly heated and will be discharged into the combustion chamber in such condition that it will aid 25 greatly in the process of combustion and can never exert a checking influence on the fire. The entire device is out of the way while fuel is being introduced and while the fire is being stirred and cleaned; it may be placed 30 above, below or at the sides of the door opening; and it may be adjusted at any angle so as to secure the best heating effect on the incoming air and deliver the air at the most advantageous points and at the 35 most advantageous angles.

While we have illustrated and described with particularity only a single preferred form of our invention, we do not desire to be limited to the exact structural details thus 40 illustrated and described; but intend to cover all forms and arrangements which come within the terms employed in the definitions of our invention constituting the appended claims.

We claim:

1. A device of the character described comprising a conduit adapted to lie in and at one side of the door opening of a furnace behind the door, heat interchangers at one end of said conduit and at opposite sides 50 thereof in position to lie within the furnace beside the door opening, said conduit having an air inlet and said heat interchangers having an air outlet, said heat interchangers being connected to said conduit by universal 55 joints.

2. In combination with a furnace having a door opening, a combustion chamber, and a furnace door, of a chamber formed on the rear side of the door and having an opening 60 leading through the door to atmosphere, a conduit lying within the door opening and abutting against said chamber when the door is closed, said conduit and said chamber having registering passages, and heat 65 interchangers connected to the inner end of and wholly supported by the conduit and lying within the combustion chamber, said heat interchangers having discharge outlets leading into the combustion chamber. 70

3. The combination with a furnace, of a conduit adapted to be fixed in and at one side of the door opening of the furnace and behind the furnace door, said furnace door and said conduit having registering passages communicating with the outside atmosphere through the door when the door is closed, and a heat interchanger lying within the combustion chamber of the furnace and connected to the inner end of and wholly 80 supported by said conduit, said heat interchanger having a discharge outlet leading into the combustion chamber. 75

In testimony whereof, we sign this specification.

FRANK J. DELANY.
ARTHUR H. SMITH.
